(57) **CLAIM**

The ornamental design for the sensor housing, as shown and described.

DESCRIPTION

FIG. 1 is a top perspective view of the sensor housing;

FIG. 2 is top plan view of the sensor housing;

FIG. 3 is bottom plan view of the sensor housing;

FIG. 4 is a left side plane view of the sensor housing;

FIG. 5 is a right side plan view of the sensor housing;

FIG. 6 is a rear view of the sensor housing; and,

FIG. 7 is a front view of the sensor housing.

The shading lines shown within portions of FIG. 1 illustrate transparent surfaces of the claimed design.

The broken lines shown within FIGS. 1, 3, 4, and 5 illustrate features that form no part of the claimed design.
